UNITED STATES PATENT OFFICE

WHEELER H. VIBBER, OF NEW LONDON, CONNECTICUT

CONDUIT AND CIRCUIT-GROUNDING FITTING

Application filed October 13, 1927. Serial No. 225,903.

My invention relates to an improved conduit and circuit-grounding fitting designed with particular reference to grounding conduit systems to water-pipes, though not so limited; the object being to produce at a low cost for manufacture a simple, conveniently-installed, durable and reliable fitting constructed with particular reference to permitting the conduit-pipe to stand at other than 10 a right angle to the grounded-pipe and to provide efficient means for attaching the circuit-grounding wire to the grounded-pipe.

With these ends in view, my invention consists in a conduit and circuit-grounding fitting of the character described, having certain details of construction as will be herein-after described.

In the accompanying drawings:

Fig. 1 is a broken view in side elevation 20 showing one form which my improved conduit and circuit-grounding fitting may assume;

Fig. 2 is a view thereof in right-hand end elevation;

Fig. 3 is a view thereof partly in central longitudinal section and partly in side elevation;

Fig. 4 is a view thereof in transverse section on the line 4—4 of Fig. 1;

Fig. 5 is a detached perspective top view of the flexible bonding-plate;

Fig. 6 is a broken view in side elevation of a modified form of my improvement;

Fig. 7 is a corresponding view of another 35 modified form thereof; and

Fig. 8 is a view in transverse section on the line 8—8 of Fig. 7.

In carrying out my invention, as shown in Figs. 1 to 5 inclusive of the drawings, I employ a flexible bonding-plate formed between its ends 10 and 11 with a bend or offset 12 which provides for offsetting the conduit-pipe 13 from the grounded-pipe 14, such as a water-pipe, whereby a clearance-space 15 is 40 established between the inner end of the former and the exterior surface of the latter; the said bonding-plate being arranged alongside of the grounded-pipe and substantially parallel therewith. The end of the conduit 13 45 is capped by a standard stamped bushing 16

located in the said space 15 and held in place by screws 17 passing through the end 10 of the plate, but said bushing might be riveted in place, if preferred. The said bushing 16 provides a smooth outlet from the conduit-pipe of the stranded grounding-wire 18, which may or may not be insulated as at 19, which in the construction now being described passes through a clearance-hole 20 in the bend or offset 12 in the bonding-plate. 55 60

For solidly securing the bonding-plate to the grounded-pipe 14, its end 11 is formed, as shown, with a shallow central longitudinal groove 21 (Fig. 2), which receives a portion of the surface of the said pipe, though this groove 20 is not essential. Preferably, also, the edges of the end 11 of the plate are symmetrically bent downward as at 22, as also clearly shown in Fig. 2. One edge of the said end 11 of the plate is provided with two open 70 slots 23, while the opposite edge is provided with correspondingly-located holes 24, these slots and holes receiving the threaded bolt-like ends 25 of two straps 26 and 27 which embrace the grounded-pipe 14 and which are drawn solidly thereupon by nuts 28 applied to the bolt-like ends 25 of the said straps, the slots 23 facilitating the installation of the straps upon the pipe 14. The straps 26 and 27 are bent to fit the grounded-pipe, and are 75 80 made long enough to adapt them to be fitted to different sizes of pipe, which may vary considerably in size.

As shown, the stranded wire 18, after passing through the clearance-hole 20, is clamped 85 between the outer face of the inner portion of the end 11 of the bonding-plate, and a transversely-arranged combined coupling- and contact-plate 29 clamped against it by the nuts 28 of the strap 26, whereby the stranded 90 grounding-wire 18 is firmly gripped in place. The stranded wire 18 is then, as shown, passed through a clearance-hole 30 in the end 11 of the bonding-plate and gripped between the exterior surface of the grounded-pipe 14 and 95 the bottom of the longitudinal groove 21 in the plate, as clearly shown in Fig. 2, the nuts 28 of the strap 27 being turned to grip the stranded wire at this point.

Inasmuch as the bonding-plate is flexible. 100

it may be bent as required to accommodate the position of the conduit 13, in case the same does not, in any given installation, naturally stand at a right angle to the grounded-pipe 14. This feature of my improved conduit and circuit-grounding fitting is of great convenience in many situations, as it not only saves material, but often a great amount of time and labor.

10 In the modified construction shown by Fig. 6, the bonding-plate is bent or returned upon itself to form a bend or offset 31, whereby a space 15 is produced to separate the end of the conduit 13 from the grounded-pipe 14, alongside of which the main part of the plate is arranged, as in the construction shown in Figs. 1 to 5 inclusive. In this construction, the plate is furnished with a clearance-opening 32 through which the stranded grounding-wire 18 passes in position to be gripped directly between the inner face of the end 11 of the plate and the exterior surface of the pipe 14 by the strap-bolts 26 and 27. If preferred, however, the stranded wire may be 20 passed between the plate 29 and the outer face of the said end of the bonding-plate. In this construction, also, the inner end of the bonding-plate is longitudinally grooved and bent, as best shown in Fig. 2.

15 25 30 35 40 45 50 55 60 65 70 75 80 85 90 95 100 105 110 115 120 125 130

11 In the modified construction shown by Figs. 7 and 8, the bonding-plate is formed with a bend or offset 12 between its ends 10 and 11 and is firmly secured to the grounded-pipe 14 by means of a strap 33, the ends of which are secured together by a clamping-screw 34 passing through a nut 35 confined in place by bending one end of the strap 33 upon itself, as at 36. In this construction, the edges of the end 11 of the plate are bent inwardly, as at 38, as shown in Fig. 8.

I claim:

1. A conduit and circuit-grounding fitting comprising a relatively narrow plate adapted to be placed alongside a grounded-pipe, substantially parallel therewith, and shaped at one end to form an offset therefrom, whereby a clearance space is formed between it and the said pipe, means for securing the opposite end of the said plate to the grounded-pipe in parallelism therewith, and means for anchoring to the offset end of the plate a conduit pipe, which enters the said space.

2. A flexible conduit and circuit-grounding fitting comprising a relatively narrow plate adapted to be placed alongside a grounded-pipe, substantially parallel therewith, and shaped at one end to form an offset therefrom, whereby a clearance space is formed between it and the said pipe, means for securing the opposite end of the said plate to the grounded-pipe in parallelism therewith, and means for anchoring to the offset end of the plate a conduit pipe, which enters the said space.

3. A conduit and circuit-grounding fitting

comprising a relatively narrow plate adapted to be placed alongside a grounded-pipe, substantially parallel therewith, and shaped at one end to form an offset therefrom, whereby a clearance space is formed between it and the said pipe, means for securing the opposite end of the said plate to the grounded-pipe in parallelism therewith, and means for anchoring to the offset end of the plate a conduit pipe, which enters the said space, and the said plate being formed with a clearance-opening for the passage of a grounding-wire from the conduit-pipe into position to lie alongside the grounded-pipe.

4. A conduit and circuit-grounding fitting comprising a relatively narrow plate adapted to be placed alongside a grounded-pipe, substantially parallel therewith, and shaped at one end to form an offset therefrom, whereby a clearance space is formed between it and the said pipe, means for securing the opposite end of the said plate to the grounded-pipe in parallelism therewith, means for anchoring to the offset end of the plate a conduit pipe, which enters the said space, and a bushing located in the said space and secured to the offset end of the plate in position to cap the inner end of the conduit-pipe.

5. A conduit and circuit-grounding fitting comprising a relatively narrow plate adapted to be placed alongside a grounded-pipe, substantially parallel therewith, and shaped at one end to form an offset therefrom, whereby a clearance space is formed between it and the said pipe, means for securing the opposite end of the said plate to the grounded-pipe in parallelism therewith, means for anchoring to the offset end of the plate a conduit pipe, which enters the said space, and the end of the plate applied to the grounded-pipe, being longitudinally grooved for the reception of the grounding-wire.

6. A conduit and circuit-grounding fitting comprising a relatively narrow plate adapted to be placed alongside a grounded-pipe, substantially parallel therewith, and shaped at one end to form an offset therefrom, whereby a clearance space is formed between it and the said pipe, and the opposite end of the said plate having its opposite edges adapted for the reception of the bolt-like ends of a strap passing over the grounded pipe for the attachment of the fitting thereto in parallelism therewith, and means for anchoring to the offset end of the plate a conduit pipe, which enters the said space.

7. A conduit and circuit-grounding fitting comprising a relatively narrow plate adapted to be placed alongside a grounded-pipe, substantially parallel therewith, and shaped at one end to form an offset therefrom, whereby a clearance space is formed between it and the said pipe, and the opposite end of the said plate having its opposite edges adapted for the reception of the bolt-like ends of a

strap passing over the grounded-pipe for the firm attachment of the plate thereto in parallelism therewith, and the said end of the plate being longitudinally grooved and having its edges symmetrically bent alongside the groove, and means for anchoring to the offset end of the plate a conduit pipe, which enters the said space.

In testimony whereof, I have signed this
10 specification.

WHEELER H. VIBBER.
